ATTORNEYS.

UNITED STATES PATENT OFFICE.

WILLIAM R. BUTNER, OF YERINGTON, NEVADA, ASSIGNOR OF ONE-THIRD TO GEORGE R. MAGEE, OF YERINGTON, NEVADA.

CLOTHESPIN.

Application filed May 9, 1927. Serial No. 190,051.

The present invention relates to improvements in clothes pins and its general object is to provide a clothes pin that may be cheaply manufactured, easily applied, and maintains a firm grip on the clothes suspended from a line. It is particularly proposed to provide a clothes pin that will effectively clamp itself to a clothes line and to clothes suspended therefrom, whereby the clothes are firmly held against movement in the direction of the line. It is proposed to utilize for this purpose a clothes pin which produces a twist in the clothes suspended from the line, whereby the clothes are prevented from shifting.

It is further proposed to provide a clothes pin that may be conveniently used in connection with different sizes of clothes lines, and will retain a firm grip on a thin clothes line as well as on a heavy one.

Further objects and advantages of my invention will appear as the specification proceeds.

The preferred form of my invention is illustrated in the accompanying drawing, in which

Figure 1 shows a perspective view of my clothes pin;

Figure 2 a side view thereof;

Figure 3 a side view of the clothes pin as it appears when used in connection with a clothes line and laundry suspended therefrom, with certain portions broken away; and

Figure 4 a section taken along line 4—4 of Figure 3.

While I have shown only the preferred form of the invention, I wish to have it understood that various changes or modifications may be made within the scope of the claim hereto attached without departing from the spirit of the invention.

In its preferred form, my clothes pin 1 is preferably made of a single piece of wire turned into a coil 2 intermediate the length thereof, so as to form two legs 3 and 4, the leg 4 being about twice the length of the leg 3, and being turned upon itself as shown at 6, to form two spaced strands 7, the extreme end of one of the strands being looped around the coil 2 as shown at 8 to prevent the coil from spreading.

The leg 3 is slightly longer than the leg 4 in its final form, and its extreme end is curved as shown at 9 to rest in an indenta-

tion 11 of the other leg, at the bend 6 thereof. The coil 2 has a spring action which causes the end of the leg 3 to be normally seated in the bend 6, but yields to pressure when the pin is forced over a clothes line 60 between the seat or bend 6 and the curved end of the leg 3, so that thereby the two legs are spread for sliding of the clothes line.

The leg 3 is normally disposed between the two strands of the leg 4, and the two legs are formed with registering bends 12 and 13 intermediate their length, these bends serving to receive the clothes line between the same. Below the bends 12 and 13 the two legs 3 and 4 present curved sections 16 70 arranged in such a manner that normally the curved section of the leg 3 enters the space between the curved sections of the leg 4 and exercises, under the influence of the coil 2, clamping action upon a piece of laundry suspended from the clothes line, by twisting the piece of laundry out of shape over a limited area thereof.

The leg 3 is preferably formed with a projecting section 17 by means of which it 80 may be more easily manipulated for applying and removing the clothes pin.

The manner of using my invention is apparent from the foregoing description. After a piece of laundry shown at 18 in Figure 85 3 has been placed over the clothes line 19 in the manner illustrated, the extreme end of the clothes pin is placed on top of the clothes line and a piece of laundry suspended therefrom, so that upon downward pressure the 90 clothes line wedges itself between the bend 6 of the leg 4 and the curved end 9 of the leg 3, and causes the two legs to separate. Further downward push causes the two legs to slide over the clothes line, and the laundry, 95 until the clothes line finally is seated between the two bends 12 and 13 in the two legs. At this time the lower curved section 16 of the leg 3 is still within the confines of the curved sections 16 of the leg 4 and exercises a twisting action on the cloth which prevents shifting movement of the latter. It will be noted that the particular shape of the clothes pin causes the same to assume its natural clamping position relative to the 100 clothes line whenever the latter is anywhere near the bends 12 and 13, because the spring action of the loop 12 causes the pin to ride upward or downward as the case may be, for bringing the bends 12 and 13 into engage- 110

ment with the clothes line. The projection 17 facilitates the handling of the clothes pin, particularly the removal of the same.

I claim:

- 5 A clothes pin constructed from a single piece of wire comprising a pair of legs connected to each other by a coil that has spring qualities for urging the legs into contact with each other, one of said legs being U-shaped and having a rounded closed end for removably receiving the other leg, the

rounded end normally contacting with the other leg, said legs having registering bends intermediate their length for receiving a clothes line therebetween, said U-shaped leg 15 having its free end fashioned into a loop for receiving the coil and for preventing the coil from spreading, the loop engaging with the top of the coil, and the other leg having a projecting portion for facilitating 20 the removal of the clothes pin.

WILLIAM R. BUTNER.
